UNITED STATES PATENT OFFICE.

ROBERT S. PELLETTE, OF KENNETT SQUARE, PENNSYLVANIA, ASSIGNOR TO AMERICAN ROAD MACHINERY COMPANY, INC., OF KENNETT SQUARE, PENNSYLVANIA, A CORPORATION OF DELAWARE.

TRACTOR SNOWPLOW.

Application filed March 15, 1926. Serial No. 94,664.

My invention relates to snow plows and more particularly to plows of the V type adapted to be propelled or pushed by means of a tractor.

5 In plows of the character to which my invention pertains, the plow proper is positioned in front of a frame within which a tractor is admitted and to which it is secured, either at its front end or through 10 connections with the draw bar of the tractor. The plow proper is secured to the frame, usually in such a manner that it may be lifted vertically or tilted up when not plowing and hoisting means carried by the frame 15 are provided for adjustment of the plow.

Plows of the character indicated have proven substantially satisfactory, but have been found open to certain criticisms which materially effect their efficiency. For example, when such a plow is utilized in snow of substantial depth, it has been found that the snow plowed out tends to fall back into the cut below the plow and further, that on attempting to plow out an old cut after a 25 fresh storm, the sides of the old cut prevent the plow from disposing of the fresh snow. Further, if it be necessary to plow hard snow, which offering substantial resistance to the plow tends to lift its nose, the plows 30 known heretofore ride up on the snow and are inefficient.

Now it is an object of my invention to provide a plow, which will effectively dispose of the snow plowed out in such a manner that the cut may be subsequently re-plowed without difficulty and in an effective manner.

Another object of my invention is to provide a plow which may be readily adjusted 40 so as to avoid any riding up of the nose of the plow when plowing in hard snow.

Further objects of my invention are to provide a plow of the character indicated which will be highly efficient and durable 45 and at the same time simple of operation and manufacture.

Having now indicated, in a general way, the nature and purpose of my invention, I will proceed to a detailed description thereof with reference to the accompanying draw-

ings in which there has been illustrated a preferred embodiment and in which:—

Figure 1, is a side view of a plow embodying my invention.

Figure 2, is a plan view of the plow shown in Figure 1.

Figure 3, is a front view of the plow shown in Figure 1.

In the several figures the plow is formed by the converging blades *a*, which are braced by means of a framing *b* composed of channel members secured to each other and to the blades. Beneath the nose of the plow is positioned a roller *c* and rollers *d* are positioned for the support of the blades between 65 their ends.

e indicates the front member of a frame for the reception of a tractor which is secured to the frame through connection with brackets *f*. The plow is connected to the frame through brackets *g*, secured to the frame near the lower end thereof, and providing vertical tracks for carriages formed by a pair of rollers *h* supporting a body or frame *i*. The carriages are retained for vertical movement in the brackets by means of rods *j* secured to the brackets and upon which the rollers bear. The plow is pivotally connected to the carriages or runners close to the bottom of the plow by means of 80 brackets *k* secured to the framing *b* and pivotally connected with the bodies *i* by pins *l*.

By virtue of the form of connection between the plow and tractor frame, the plow is pushed directly by said connections and 85 may be raised vertically in the brackets *g* or tilted on the pins *l* and for this purpose there is mounted on the tractor frame a derrick *m* which serves to support a hoist formed by a gear *n* mounted on a cross shaft *o*, which serves as a winding drum, and a worm *p* suitably supported in mesh with the gear and adapted to be rotated manually through a shaft *q*. Secured to the shaft *o* is a pair of chains *r* to the free ends of each 95 of which are secured a pair of chains *s* provided at their ends with hooks *t*. The chains *s* are adapted to be connected to the front and rear portions of the plow by passing through eyes *u*, secured to the plow, and en- 100

gaging with themselves through the medium of hooks t , as illustrated in Figure 1.

It will be observed that the length of the chains s and hence the length of the connection between the front and back of the plow and the ends of chains r , may be varied by hooking the chains with themselves at different points. Thus by shortening the chains s connecting the rear of the plow with chains r and lengthening the chains s connecting the front of the plow with chains r , upon operating the hoist the rear of the plow will be lifted ahead of the front which will thus be allowed to tilt down and cause the plow to dig into the snow. By reversing the relative length of the front and rear chains s the front of the plow may be lifted ahead of the rear and the front tilted up preventing the plow from digging into the snow and enabling the upper portion of a deep drift to be plowed out without stalling the plow.

The plow blades a , which as has been described, converge to form a V plow, are normally substantially rectangular and formed with a concave face in order to pick up and pass the snow laterally from the rear of the blades. Removably secured to the upper portion of the rear end of each of the blades is a flared extension v , which extends above and beyond the end of the blade. The extensions v are preferably formed with a concave face generally conforming to the curve of the face of the blades and in their

extension beyond the ends of the blades are formed with upwardly curved lower edges 35 and curved ends. Their upper edges extend upwardly above the blades in a substantially straight line.

It will be observed, from an inspection of Figure 3, that in operation the extensions v 40 will act to convey snow picked up and conveyed by the blades a and at the same time will act to prevent the forming of a shoulder in the cut made by the plow; with the result that snow will not fall back behind the plow and on replowing there will be no interference with the disposal of fresh snow, which will be handled by the blades and extensions 45 with the same facility as the original snow.

I claim:—

In a snow plow, a supporting frame, a plow, and means for supporting the plow from the frame whereby the plow is arranged to be pushed by the frame and is capable of pivotal movement, said means 55 including a supporting member having connection with the plow, said connection being adjustable relatively to the center of gravity of the plow to determine its normal pivotal movement, and means for raising said supporting member.

In testimony of which invention, I have hereunto set my hand, at Kennett Square, Pa., on this ninth day of March, 1926.

ROBERT S. PELLETTE.
